LIQUID DISPENSER AND COOLER

José Sierra Rosado, San Juan, P. R.

Application February 14, 1936, Serial No. 63,960

3 Claims. (Cl. 225—21)

This invention appertains to new and useful improvements and means for dispensing and maintaining cool various kinds of liquid substances such as milk and various beverages.

5 The principal object of the present invention is to provide a dispenser of compact construction and one in which beverage can be maintained cool without constant attention.

10 Another important object of the invention is to provide a liquid container in which milk can be placed and from which can be dispensed in an easy and convenient manner wherein means is provided for permitting the milk to be agitated from time to time to maintain the cream thoroughly mixed with the precipitated portion of the milk.

15 These and various other important objects and advantages of the invention will become apparent to the reader of the following specification.

20 In the drawings:

Figure 1 represents a side elevational view of the dispenser.

Figure 2 represents a top plan view of the dispenser with the dome removed.

25 Figure 3 is a vertical sectional view through the dispenser.

Figure 4 represents a horizontal sectional view taken substantially on line 4—4 of Figure 3.

Figure 5 is an enlarged fragmentary detailed 30 sectional view taken substantially on line 5—5 of Figure 2.

35 Referring to the drawings wherein like numerals designate like parts, it can be seen in Figure 3, that numeral 5 represents an outside shell which is provided at its bottom with an annulus 6 formed with depending legs 7.

The upper edge of this shell 5 is disposed inwardly to provide a horizontal flange 8 having the downturned circumferentially extending lip 9 at its edge portion for engaging under the outturned flange 10 at the upper end of the inner receptacle 11, which receptacle serves to contain the liquid to be dispensed.

40 An annular partition 12 is located in the compartment 13 between the shell 5 and the inner receptacle 11 and this is preferably secured by soldering, welding or some other suitable means to the inner side of the shell 5, so that the inner receptacle 11 can readily be removed. This partition 12 is provided with openings 14 through which melted ice can drain to reach the drain compartment 15. The compartment 13 is filled with ice and salt for maintaining the contents of the receptacle 11 cool.

45 50 55 A closure plate 16 is provided for the top of

the receptacle 11 and this is provided inwardly of its periphery with a downwardly disposed flange 17. The flange 17 is annular and intended for snug fit into the upper portion of the receptacle 11 as shown in Figures 3 and 5. The portion of the periphery of the cover 16 extending beyond the flange 17 overlaps the flange 8 of the shell 5 as well as the flange 18 at the upper edge of the receptacle 11 and interposed between the portion of the cover 16 and the flange 18 is the packing ring 19. Lugs 20 extend outwardly from the peripheral portion of the cover 16 and are apertured. Bolts 21 extending upwardly from the flange 8 extend through spacers 22 and through the openings in the lugs 20 and are equipped with wing nuts 23 which when tightened downwardly against the lugs 20 cause the cover 16 to bear snugly over the upper end of the receptacle 11.

5 10 15 20 25 30 35 40 45 50 55 Numeral 24 is a conical shaped dome having an upstanding bearing 25 at its apex through which the rod 26 is slidable. The hood 24 is provided with hasps 27 engaging over the keepers 28 on the shell 5 and padlocks 29 or other fastening means are engaged with the keepers 28.

Numeral 30 represents an upright on the dome 24 which is braced by the arms 31 extending therefrom and connecting the bearings 25 at the apex of the hood 24. The upper end of the upright 30 is slotted as at 32 and through this extends the elongated bar 33 which is pivotally connected to the upright 30 at the point where it extends through the slot 32 and more specifically as at 34.

The end 35 of the bar 33 serves as a handle, 35 while the opposite end is slotted as at 36 to receive the lateral pin 37 at the upper end of the rod 26.

A conical shaped agitator 38 provided with 40 perforations is secured as at 39 to the lower end of the rod 26.

If a suitable liquid refrigerant is to be used in the chamber 13 an inlet pipe 40 is provided for the same, while the pipe 41 represents a 45 drain for the chamber 15.

Numeral 42 is the drain faucet whereby liquid is dispensed from the receptacle 11.

When the structure is being used for dispensing of milk, it is necessary to keep the milk agitated now and then to maintain the cream thoroughly mixed with the rest of the milk substance.

50 55 While the foregoing specification sets forth the invention in specific terms, it is to be understood

that numerous changes in the shape, size and materials may be resorted to without departing from the spirit or scope of the invention as claimed hereinafter.

5 Having thus described the invention, what is claimed as new is:

1. A dispensing device of the character described comprising a shell, an inside receptacle detachably supported in the shell, discharge 10 means communicating with said receptacle, means for spacing the receptacle from the shell, a cover for the receptacle, a detachable dome for the shell and positioned over said cover, a plunger in the receptacle, a rod extending from the plunger through the cover and through the dome 15 and means on the dome whereby the rod and plunger can be reciprocated.

2. A dispensing device of the character described comprising a shell, an inside receptacle detachably supported in the shell, discharge 20 means communicating with said receptacle, means for spacing the receptacle from the shell, a cover for the receptacle, a detachable dome

for the shell and positioned over said cover, a plunger in the receptacle, a rod extending from the plunger through the cover and through the dome and means on the dome whereby the rod and plunger can be reciprocated, said means 5 consisting of an upright on the dome, a bar rockable on the upright and a pin and slot connection between the rods and the bar.

3. A dispensing device of the character described comprising a shell, an inside receptacle 10 detachably supported in the shell, discharge means communicating with said receptacle, means for spacing the receptacle from the shell, a cover for the receptacle, a detachable dome for the shell and positioned over said cover, a plunger 15 in the receptacle, a rod extending from the plunger through the cover and through the dome and means on the dome whereby the rod and plunger can be reciprocated, said cover being provided with packing and clamp means 20 whereby the cover can be firmly secured over the upper portion of the receptacle.

JOSÉ SIERRA ROSADO.
